UNITED STATES PATENT OFFICE

162,987

PORTABLE SPRAYING DEVICE

Hyman Richard Rich, New York, N. Y., assignor
to West Disinfecting Company, Long Island
City, N. Y.

Application December 28, 1949, Serial No. 6,864

Term of patent 14 years

(Cl. D91—1)

To all whom it may concern:

Be it known that I, Hyman Richard Rich, a citizen of the United States of America and resident of New York city, county of Queens, and State of New York, have invented a new, original, and ornamental Design for Portable Spraying Device, of which the following is a specification, reference being had to the accompanying drawing, forming part thereof.

Fig. 1 is a side view in perspective of the portable spraying device, showing my new design, the other side of the device being substantially like the side shown.

Fig. 2 is a front elevation of same.

The dominant features of my design reside in the portions shown in full lines.

I claim:

The ornamental design for a portable spraying device, substantially as shown and described.

HYMAN RICHARD RICH.
